Attorney,*

UNITED STATES PATENT OFFICE.

JOSEPH C. HARVEY, OF CHICAGO, ILLINOIS, ASSIGNOR TO MOON-HOPKINS BILLING MACHINE COMPANY, OF ST. LOUIS, MISSOURI, A CORPORATION OF MISSOURI.

TALLY-ROLL ATTACHMENT.

1,072,452.

Specification of Letters Patent. Patented Sept. 9, 1913.

Application filed April 5, 1912. Serial No. 688,752.

To all whom it may concern:

Be it known that I, JOSEPH C. HARVEY, a citizen of the United States, residing at Chicago, Illinois, have invented a certain new and useful Improvement in Tally-Roll Attachments, of which the following is a full, clear, and exact description, such as will enable others skilled in the art to which it appertains to make and use the same, reference being had to the accompanying drawings, forming part of this specification, in which—

Figure 1 is a plan view of my attachment in position. Fig. 2 is a side view of my attachment in position, partially in section.

My invention relates broadly to writing machines and specifically to an attachment for a combined typewriting and computing machine.

The principal object of my invention is to produce a device of the class described upon which may be listed all of the successive computations or transactions performed by the machine.

Another object of my invention is to produce a device of the class described which does not require the use of carbon or transfer paper.

A further object of my invention is to produce a device of the class described particularly adapted for use on combined typewriting and adding machines.

In the use of billing machines or combined writing and computing machines in which in the course of business a large number of separate and individual accounts or statements are usually prepared, it is often desirable to retain a complete unitary record of all the separate and individual computations, accounts, or transactions prepared upon the machine. For these records, only the successive amounts are required, the names or writing applying thereto being unnecessary. By the device hereinafter described, the machine is enabled to make such an independent and unitary list simultaneously with the preparation of the individual or separate accounts.

The form of my invention illustrated in the drawings is designed for application to a combined typewriting and computing machine, wherein there are separate printing mechanisms for the typewriting machine and the computing machine both operating upon a common platen.

As illustrated, the typewriter is provided

with a frame 1, upon which are mounted ribbon guides 2 which guide and vibrate the ribbon 3. Supported on said guides 2 over the ribbon 3 is the guard plate 4 which is provided with slots 6 for the passage of the ribbon and a wide opening 7 intermediate said slots for the reception of the type bars 8 carrying type 8^a of the adding machine and portions of my attachment. By means of the screws 9 there is secured to the upper front portion of the frame 1, an oblong plate 10 which carries at its extreme front end the yoke 11 equipped with a spindle 12 for holding a roll of paper 14. At the extreme rear end of the plate 10 are mounted two small rollers 15 and 16 for the purpose of transmitting and guiding the strip of paper 17. Intermediate the roll 14 and the rear pair of rollers is mounted on the plate 10 a pair of ears 18 provided with a spindle 19 carrying the reel 20. Upon one end of the spindle 19 is carried the toothed wheel 21 and upon the hub of the spindle 19 adjacent thereto is mounted the rocking lever 22 which, at its forward end is drawn downward by the coil spring 24 anchored in the plate 10. At its other end, the lever 22 carries the pawl 25 which is normally forced into engagement with the rack wheel 21 by the spring 26. On a downwardly projecting portion of the lever 22 is provided the lug 27 projecting laterally therefrom. A stop pin 28 is carried by the ear 18 and operates upon the end of the pawl 25 to limit the movement of the lever 22 under the influence of the spring 24. To the rear of the reel 20, the small guide roller 29 is pivoted in the ears 18 close to the plate 10. At the point X, the plate 10 is down-set and bifurcated by an opening 30, within which opening the type bars 8 operate. At Y, the aperture 30 is widened by an in-set which provides an aperture through which the type 31 of the letter printing mechanism operate.

The two branches of the bifurcated portion of the plate 10 are provided at their rear extremities with notches 32 which engage pins 34 which are set in the frame 1, which pins taper from each end toward the middle, as illustrated in Fig. 2, so as to form positioning means for holding the notched end of the plate 10 at the proper elevation. One of the branches of the bifurcated plate 10 has a projecting portion 35 which is bent downwardly so as to lie

below the guard plate 4. Between the projecting portion 35 and the guard plate 4 and below the ribbon 3, passes the link 36 which is guided at its forward end by a 5 pin 37 secured to the track 38 and operating through a slot 39 in the link 36. At its front tip, the link 36 is provided with a flattened head 40 which abuts against the projection 27 of the lever 22. At the 10 point Z, the link 36 is bent downward so that it may pass below the guard plate 4, and at its rear end, the link 36 is provided with an up turned ear 41. A post 42 is secured to the frame 1 and carries, pivoted 15 at 44 to its upper portion, a lever 45 having a downwardly extending arm 46 pivoted to the ear 41, an upper arm 47, and a lower arm 48. A link 49 is positioned in the frame and adapted to be reciprocated 20 vertically from the line spacing mechanism. In its upper end, this link 49 is provided with a projection 50 which operates between the arms 47 and 48 of the lever 45. The paper 17 is of such transparency that 25 printing on one side is visible through it. This paper is supplied in rolls 14 mounted on the spindle 12, and as fed to the machine, passes from said roll rearwardly across the plate 19, over the type 8 of the 30 adding machine but to one side of the opening Y, over the roll 15, and then back forward under the roll 16, under the ribbon 3, under the roll 29 and on to the reel 20.

The parts thus described are operated in 35 the following fashion. Sheets for the reception of the individual bills or items are introduced in the well known fashion behind the platen 51 of the paper carriage 52 and between it and the ribbon 3, in which 40 position it may be printed upon by the type 31 of the letter printing mechanism which strikes the ribbon 3 at the printing point through the aperture Y to one side of the tally strip 17. The number printing type 45 8 likewise prints upon the individual sheets through the ribbon 3, but in so doing the number printing type strikes upon the lowermost pole of the tally strip 17 and forces the uppermost layer of said strip against the 50 under side of the ribbon 3, whereby a reverse impression is received upon the upper side of said tally strip. At each operation of the line spacing mechanism, the link 49 is reciprocated downwardly. In this movement 55 of the link 49, the projection 50 contacts with the arm 48 of the lever 45, forcing it downwardly and forwardly and pushing the link 36 forwardly. This forward movement of the link 36, by virtue of the engagement of the head 40 of said link with the projection 27, rocks the lever 22 and causes the pawl 25 to rotate the rack wheel 21. The rack wheel 21 rotates the spindle 19 and winds the tally strip on to the 60 reel 29 thus feeding said strip the proper 65

distance for the line spacing of the numbers. As seen through the transparent strip 17, the numbers printed thereon in reverse order appear in their normal order, and as all numbers printed by the adding machine type are printed upon this tally strip in the manner above described, a complete record is retained thereon of all transactions or computations made by the machine. 70

While the foregoing description and illustration shows my invention applied to one specific type of billing machine, it is obvious that by changing the structure, it may be applied to other forms of machines, or that other modifications and changes of structure may be made without departing from the scope of my invention. 75

What I claim is:

1. In combination with a billing machine having a platen, separate sets of printing type, and an inked ribbon positioned between said platen and said type and adapted to be struck by type of one of said sets, a tally strip positioned between the other of said sets of type and said ribbon. 80

2. In combination with printing mechanism having printing type, an inked ribbon, a tally strip and means for guiding said tally strip rearwardly over said type and forwardly under said ribbon. 90

3. In combination with a platen and type, a continuous tally strip, means for feeding a portion of said tally strip between said type and said platen and an integral portion of said strip between said first mentioned portion and said platen. 100

4. A tally roll attachment comprising a plate, a supply roll at one end of said plate, a guide roll at the other end of said plate, and a receiving roll intermediate said rolls. 105

5. In a tally roll attachment, a plate, a supply roll at one end of said plate, a guide roll at the other end of said plate, and feeding mechanism intermediate said rolls. 110

6. In combination with printing mechanism having an inked ribbon, a tally roll attachment comprising a plate, a tally strip mounted on said plate, and means for moving said strip in two directions intermediate said plate and said ribbon. 115

7. In a writing machine, the combination of a type, a platen for supporting paper, a tally strip, and a ribbon arranged to print from the same portion thereof upon both the tally strip and paper carried by the platen at the same operation of the type. 120

8. In a writing machine, the combination of a platen for supporting paper, a tally strip, means for supporting said strip in position, an inked ribbon, and a type arranged to print from the same area of said ribbon upon both said tally strip and paper supported on said platen at the same operation. 125

9. In a billing machine in combination, 130

an inked ribbon, a type, a second kind of type, a platen adapted to support paper in position to receive impressions of both of said kinds of type from said ribbon, and a 5 tally strip supported in position to receive impressions of said second mentioned type from said ribbon at the same time that impressions of said second mentioned type are made upon the paper supported by the 10 platen.

10. In a billing machine, the combination of a platen adapted to support paper, a tally strip, type adapted to strike paper supported by said platen, type adapted to strike said 15 tally strip, and a strand of ribbon adapted

to coöperate with all of said type, said tally strip and the paper supported on the platen to make printed impressions of said first mentioned type upon the paper supported on the platen and of said last mentioned 20 type upon the tally strip and upon the paper supported on the platen.

In testimony whereof I hereunto affix my signature in the presence of two witnesses, this 29th day of March, 1912.

JOSEPH C. HARVEY.
